UNITED STATES PATENT OFFICE

LEON D. TITUS, OF PORT ARTHUR, TEXAS, ASSIGNOR TO THE TEXAS COMPANY, OF NEW YORK, N. Y., A CORPORATION OF DELAWARE

CAPPING APPARATUS

Application filed January 24, 1928. Serial No. 242,665.

My invention relates generally to apparatus for closing or capping containers, and more particularly to a hand tool adapted to accomplish this result. In the past considerable difficulty has been experienced in plants where automatic can filling and capping machinery has been employed due to occasional leaky caps where they have not been properly applied. Under such circumstances it has frequently been the practice to manually insert the defective can, after refilling, under the capping tool of the automatic machine to apply new caps. Obviously this has been a slow and cumbersome procedure. The present invention contemplates a relatively small hand tool for recapping such leaky cans and at the same time it provides a device which may be used as an auxiliary unit in plants where automatic can-filling and capping machinery is employed, or as a main unit in smaller plants where such work is done by manual labor or mechanically but without the employment of automatic machinery. The novel construction is such, furthermore, that the apparatus may be readily adapted to be driven mechanically, all of the operating parts being driven from a single rotatable element.

In the accompanying drawings which illustrate one form of the invention having the above objects in view,

Figure 1 is a view in side elevation of a hand capping tool constructed in accordance with the invention.

Figure 2 is a plan view of the same.

Figure 3 is an elevational view partly in section.

Figure 4 is a detail view of a portion of the device.

Figure 5 is a detail view partly in section of the lower end of the device showing a cap and opening in the can in relation to the tool.

The capping tool includes a main or vertical spindle or shaft 1 which, in the use of the device, remains idle, and to which is rigidly fastened a handle 2 and a sleeve 3 which serves as a mounting for certain other parts as will be hereinafter described.

A bevel gear 4 is loosely mounted on a horizontal shaft or stud 5 suitably secured

to and extending from a radial hub integral with the sleeve 3. Fast to the bevel gear 4 is a hub having a crank arm 6 integral therewith, crank 6 being actuated by hand power to drive the gear. A bevel gear 7 meshes with bevel gear 4, deriving its power therefrom, and is pinned or otherwise secured to a sleeve 8^a through which it transmits power to a spur gear 8 also attached to the sleeve. The sleeve 8^a being secured to the upper reduced portion of a sleeve 13 which is loosely mounted on the spindle 1, is the medium of power transmission between gears 7 and 8 and the sleeve 13.

A spur gear 9 having the same number of teeth as gear 8, is meshed with the latter and derives power therefrom. Gear 9 is secured to and so actuates a spur gear 10 which has a lesser number of teeth than the gear 9. Both gears 9 and 10 are supported by means of a stud 11 which has an enlarged horizontally disposed head providing a shoulder to support the gears 9 and 10, the bottom surface of gear 10 resting upon the shoulder of the enlarged head of stud 11. As shown, the gear 9 may be mounted upon and secured to the hub of gear 10. The upper end of the stud 11 extends into a horizontally projecting arm 3^a integral with or secured to the sleeve 3. Being securely fastened in the arm 3^a as by means of a pin, the stud 11 provides a rigid support for gears 9 and 10.

A spur gear 12 having a greater number of teeth than gear 10, preferably in the ratio of five to four, is meshed with gear 10 and derives power therefrom. A cam surface 12^a is formed upon the face of the lower vertical extension of the hub of gear 12 for a purpose which will be described hereinafter. A part of the upper extension of sleeve 13 is suitably journaled to provide a bearing for gear 12 and cam 12^a, since, as will be apparent, there will be a difference in the speeds of rotation of the elements 12, 12^a and 13.

Sleeve 13, acting also as an auxiliary support for parts to be hereinafter described, is in turn supported by a thrust ring 14 resting on a shoulder formed by an enlarged lower portion of shaft 1. It will be understood

that the sleeve 13 is mounted for free rotation on the shaft 1.

Lugs 13^a and 13^b, integral parts of sleeve 13, are provided with openings to receive a horizontal pin or trunnion 15 extending from a hub portion intermediate the ends of an arm 16, which might briefly be described as a rocker arm. An idling roller 17 in constant contact with cam 12^a, is loosely mounted upon a pin 18. The axis of roller 17 and the upper portion of pin 18 is offset from the vertical axis of arm 16 and the lower part of pin 18, thus providing an eccentric adjustment of the roller 17 relative to the arm 16. The pin 18 may be secured by set screw 19 in any position of adjustment in the arm 16, and thus serves to determine the relative position of the arm. A flat spring 20 is provided to act outwardly against arm 16 below its pivotal support 15, thus causing roller 17 to make constant contact with the cam 12^a. A crimping tool 21, formed preferably with a beveled face and a thin annular rim or bead as illustrated, and set at an angle from the axis of arm 16, although it may be desirable to use other types of crimping tools depending upon the work to be done, is provided for positively crimping down or closing over the edge of the cap. It is suitably mounted upon a ball or roller bearing formed between a hub 22 integral with or secured at an angle to the arm 16 in any suitable way, and the enlarged head of a pin 21^a, fastened into the hub by a pin or set screw.

35 A companion rotatable die 24, to co-operate with crimping tool 21 is formed preferably with an annular bead or rim at the lower end as illustrated, though here also it may be desirable to use other types of dies to co-operate with any suitable form of crimping tool 21, is provided for beading or expanding outwardly that annular portion of the vertical wall of the cap near its bottom in a manner such as when the cap is secured in the opening the said expanded portion will be immediately below the inside of the top of the can. Die 24 is mounted at the bottom of shaft 1 and is suitably journaled thereon for free rotation. The shaft is preferably provided with a suitable greasing fitting 23 for lubricating the die journal. As shown, the die mounting may consist of a large headed pin 23^a fitted into the end of shaft 1 and held in position by a cross pin or set screw.

55 In the normal position of the parts cam 12^a co-operating with roller 17 will act through arm 16 to release crimping tool 21 and, with the aid of spring 20 will cause it to assume an outward position as shown in Figure 5, to permit the introduction of the die 24 into a cap placed loosely over the opening in the can.

With the necessary clearance thus provided between the crimping tool 21 and die 24, the latter is inserted into the upper end of the

cap then maintaining the necessary pressure upon handle 2, the crank 6 is turned at a suitable speed through a number of complete revolutions, for example five turns.

By the power transmitted through the system of gears, sleeve 13 is caused to rotate about the spindle 1, whereupon the rocker arm 16, roller 17, and crimping tool 21 will be revolved bodily about the axis of sleeve 13. Roller 17 will be acted upon positively by cam 12^a during a portion of the rotation which action through arm 16 will bring the crimping tool 21 as close to die 24 as is necessary to establish their working relation for crimping in the flange on the cap and for expanding the vertical wall of the cap near its bottom. The proper spacing or working relation of crimping tool 21 and die 24 may be adjusted to suit working conditions by means of the adjustable eccentric mounting of roller 17 on the offset portion of pin 18.

It will be observed that the cam 12^a also rotates and in the same direction as the rocker arm 16 and sleeve 13 above mentioned, but preferably at a slower rate of speed, although in some cases it may be rotated faster, due to the difference in the size of gears 10 and 12, cam 12^a making only four revolutions while rocker arm 16 makes five. Thus for every five turns of the crank 6 a relative movement of one revolution between the arm 16 and cam 12^a takes place. By means of this differential gearing an automatic feature is developed, that is, by merely maintaining the necessary pressure upon handle 2 and turning crank 6, the crimping tool 21 is brought into working co-operation with the die 24 and forcibly held in this position by the cam 12^a acting upon roller 17 while the tool is being revolved about the flanged edge of the cap so that the flange on the cap is positively crimped and the annular portion of the vertical wall of the cap is expanded. Afterwards by mere continuation of the turning of crank 6 the crimping tool 21 is automatically released by action of cam 12^a and spring 20 to permit the removal of the tool and its application to another cap.

No extra manual means is required for rocking the crimping tool into and out of position. It will be understood that if the cam 12^a is so formed as to rock the arm 16 against the action of the spring 20 during one-half of the relative movement of these parts, then during five turns of the crank 6 and five corresponding rotations of the arm 16, the tool 21 will be active for two and one-half turns about the cap, thus insuring the full crimping of the cap flange and the full expanding of the cap wall. Obviously the gear ratio and cam formation mentioned are suggested for purposes of illustration only and may be varied to suit the conditions. For example, gears 8 and 9 in lieu of having the same number of teeth, may have a differ-

ent number, and produce a different gear ratio over all of the same.

Due to the fact that the die 24 is somewhat smaller than the opening in the cap, it will be drawn toward the tool 21 against the inner vertical wall of the cap and will be frictionally rotated about the spindle 1 by virtue of the contact with the cap. This is the reason for mounting the die rotatably on the spindle and for lubricating the bearing. If desired, the device may, with slight modification, be power driven rather than manually operated.

While a specific embodiment of the invention has been shown and described herein, it will be understood that it is for the purposes of illustration only and that numerous changes in the construction may be made without departing from the spirit of the invention. It is desired to be limited in this respect only by the scope of the claims which follow.

What I claim is:

1. A capping apparatus comprising a rotatable die, a crimping tool adapted to revolve about the die, means for forcibly holding the tool in working co-operation with the die and alternately permitting periodical release of the tool therefrom, and manual means for continuously revolving said crimping tool and simultaneously effecting automatic operation of said first mentioned means.

2. A capping apparatus comprising a rotatable die, a rocker arm, a crimping tool mounted on said rocker arm so as to co-operate with the die, means for revolving the rocker arm and the crimping tool about the axis of the die, and means for forcibly holding the crimping tool in working co-operation with the die and permitting the periodical release of the tool.

3. A capping apparatus comprising a rotatable die, a rocker arm, a crimping tool rotatably mounted on said rocker arm to co-operate with the die, driving means for revolving the rocker arm and the crimping tool about the axis of the die, and a cam for forcibly holding the crimping tool in working co-operation with the die and permitting the periodical release of the tool automatically in consecutive order.

4. A capping apparatus comprising a rotatable die, a rocker arm, a crimping tool rotatably mounted on said rocker arm to co-operate with the die, driving means for revolving the rocker arm and the crimping tool about the axis of the die, a rotatable cam for forcibly holding the crimping tool in working co-operation with the die, and differential gearing interposed between the driving means, the rocker arm and the cam, whereby the cam is rotated at a different speed than the rocker arm.

5. A capping apparatus comprising a ro-

tatable die, a rocker arm, a crimping tool rotatably mounted on said rocker arm to co-operate with the die, driving means for revolving the rocker arm and the crimping tool about the axis of the die, a rotatable cam for forcibly holding the crimping tool in working co-operation with the die, and differential gearing interposed between the driving means, the rocker arm and the cam, whereby the cam is rotated at a slower speed than the rocker arm.

6. A capping apparatus comprising a rotatable die, a rocker arm, a crimping tool rotatably mounted on said rocker arm to co-operate with the die, driving means for revolving the rocker arm and the crimping tool about the axis of the die, a rotatable cam for forcibly holding the crimping tool in working co-operation with the die, differential gearing interposed between the driving means, the rocker arm and the cam, whereby the cam is rotated at a slower speed than the rocker arm, and adjustable means for determining the working relation between the tool and the die.

7. A capping apparatus comprising a rotatable die, a rocker arm, a crimping tool rotatably mounted on said rocker arm to co-operate with the die, driving means for revolving the rocker arm and the crimping tool about the axis of the die, a rotatable cam for forcibly holding the crimping tool in working co-operation with the die, differential gearing interposed between the driving means, the rocker arm and the cam, whereby the cam is rotated at a slower speed than the rocker arm, and an eccentrically adjustable roller on the rocker arm co-operating with the cam for determining the working relation between the tool and the die.

8. A portable capping apparatus comprising a rotatable cylindrical die having an annular bead or enlargement at one end, a rocker arm, a crimping roller mounted on said rocker arm so as to co-operate with the die, driving means for revolving the rocker arm together with the crimping tool about the axis of the die, and a cam co-operating with the rocker arm for forcibly holding the crimping tool in working co-operation with the die and permitting the periodic release of the tool.

9. A portable capping apparatus comprising a rotatable cylindrical die having an annular bead or enlargement at one end, a rocker arm, a crimping tool mounted on said rocker arm so as to co-operate with the die, driving means for revolving the rocker arm together with the crimping tool about the axis of the die, a cam mounted to rotate coaxially with the die and co-operating with the rocker arm for forcibly holding the crimping tool in working relation to the die, an eccentrically adjustable roller on the rocker arm co-operating with the cam for determining the work-

ing relation between the tool and die, and differential gearing interposed between the driving means and the rocker arm and the cam, whereby the cam is rotated at a slower speed than the rocker arm to insure the co-operation between the crimping tool and die throughout a complete revolution.

10. A portable capping apparatus comprising a rotatable cylindrical die having an annular bead or enlargement at one end, a rocker arm, a crimping tool mounted on said rocker arm so as to co-operate with the die, driving means for revolving the rocker arm together with the crimping tool about the axis of the die, a cam mounted to rotate coaxially with the die and co-operating with the rocker arm for forcibly holding the crimping tool in working relation to the die, an eccentrically adjustable roller on the rocker arm co-operating with the cam for determining the working relation between the tool and die, and differential gearing interposed between the driving means and the rocker arm and the cam, whereby the cam is rotated at a slower speed than the rocker arm to insure the periodic release of the crimping tool from a working relation with the die after a cap has been applied.

11. A capping device comprising a cam mounted on a relatively fixed axis, a roller in constant contact therewith, an eccentrically adjustable mounting for the roller adapted to shift the axis of the roller, means for bodily swinging said carrier about the axis of the cam, and a rotary driving element adapted to operate said carrier to shift the axis of the roller and to operate said swinging means.

In witness whereof I have hereunto set my hand this 7th day of January, 1928.

LEON D. TITUS.
